UNITED STATES PATENT OFFICE.

WILLIAM H. EDSALL, OF WALLINGFORD, CONNECTICUT, ASSIGNOR TO H. L. JUDD COMPANY, INC., OF WALLINGFORD, CONNECTICUT, A CORPORATION OF DELAWARE.

CURTAIN SUPPORT.

Application filed June 20, 1925. Serial No. 38,408.

My invention relates to new and useful improvements in curtain supports, and particularly to a device which is designed to be slidably mounted upon a rod, from which 5 device curtains or draperies may be suspended.

Among the objects of my invention is the provision of a simple and efficient structure which will permit the draperies to be readily attached in and detached from their 10 position of use.

In the accompanying drawings—

Fig. 1 is a plan view;

Fig. 2 is a side view;

15 Fig. 3 is a fragmentary view, partly in section, showing how the parts are assembled.

20 1 represents an inverted L-shaped frame member. 2 represents a companion L-shaped frame member. These members overlap at their upper ends to form a splice joint. The member 1 is provided with a passage to receive a connecting bolt 3, and the member 2 is provided with a slot 4 at its extreme end, 25 of sufficient width to clear the shank of said bolt 3. The frame 1 also has an aligning means, such as a nose 5, designed to enter a recess 6 in the frame 2 when said frames are assembled. 7 is a thumb nut, adapted to the 30 threaded portion of the bolt 3. The bolt operates to hold the overlapped ends of the frame members 1 and 2 in close contact, as shown in Fig. 2, and this, with the aid of the nose 5, serves to hold the overlapped ends 35 of the frame members 1 and 2 in rigid alignment.

40 To detach the frame members the thumb nut 7 is first backed off, as shown in Fig. 3. The member 2 is then swung so that the nose 5 is disengaged from the recess 6, whereupon the parts may be separated.

45 The curtains or draperies (not shown) are attached to the frame members 1 and 2 in any suitable way and by any appropriate means. When it is desired to take the curtains down it is unnecessary to detach the same from the members 1 and 2, since that end can be accomplished by merely separating said parts 1 and 2, as above described.

By preference the frame member 1 is provided at its inner side with an anti-friction roller 8, and the frame member 2 is provided with an anti-friction roller 9. These rollers permit the curtain support to slide easily and freely on the usual curtain pole, which, 50 in use, stands between the frame members 1 and 2.

55 The frame members are preferably made from flat stock, as shown, and it is unnecessary that the lower ends of said frame members be connected.

60 I have shown my invention in only one preferred form. However, I appreciate that certain changes can be made without departing from the spirit thereof or the scope 65 of the following claims.

I claim:

1. A curtain support comprising two inverted L-shaped frame members overlapping at their upper ends, to form a splice joint, 70 a manually operable fastening device for securing said ends together, and means adjacent to and coacting therewith to hold said overlapping ends in alignment.

2. A curtain support comprising two inverted L-shaped frame members overlapping at their upper ends, to form a splice joint, a manually operable fastening device for securing said ends together, and means adjacent to and coacting therewith to hold said 80 overlapping ends in alignment, said fastening device comprising a bolt, one of said members being perforated to receive said bolt and the other being slotted at its extreme end to receive said bolt. 85

3. A curtain support comprising two inverted L-shaped frame members overlapping at their upper ends to form a splice joint, a manually operable fastening device for securing said ends together, and means adjacent thereto and coacting therewith to hold said overlapping ends in alignment, comprising a nose at the extreme end of one of said members for engaging the other member. 90

WILLIAM H. EDSALL.
